HAIR WAVING DEVICE

Arthur M. Herschensohn, Brooklyn, N. Y.

Application July 16, 1935, Serial No. 31,553

4 Claims. (Cl. 132—31)

My invention relates to improvements in hair waving devices and it consists in the novel features, which are hereinafter more fully described.

One of the objects of my invention is to provide the jaws of a spring pressed hair waving device with teeth which are disposed to have a biting action when closing on a layer or lock of hair, thereby holding the enclosed layer of hair more firmly.

Another object of my invention is to have said teeth acting on more than one layer of hair at a time, thereby insuring a firmer grip on the hair.

A further object of my invention is to have the hair waving device adapted for use on different volumes of hair.

A still other object is to have my improved hair waving device simple, durable and relatively inexpensive.

I attain these objects by the hair waving device, three forms of which are illustrated in the accompanying drawing, or by any mechanical equivalent or obvious modification of the same.

In the drawing Fig. 1 is a side elevation of one form of my hair waving device which is shown with the teeth thereof extending upwardly and the thumb-plates thereof extending downwardly.

Fig. 2 is a cross-section on the line 2—2 of Fig. 1, looking in the direction of the arrows but showing only one pair of teeth of the device.

Fig. 3 is a plan view of another form of my hair waving device, positioned as in Fig. 1;

Fig. 4 is a cross-section on the line 4—4 of Fig. 3, looking in the direction of the arrows, and also showing only one pair of teeth of the device.

Similar numerals refer to similar parts throughout the several views:

In the form of my hair waving device, which is shown in Figs. 1 and 2, 11 and 12 designate two jaws, which are hingedly connected to each other by means of a pin 13 and two pair of sockets 14 and 15, one pair on each of the jaws 11 and 12.

The pin 13 is shown as encompassed by a torsional spring 16 which is initially stressed and has its ends disposed to press against the inner sides of a pair of thumb-plates 17 and 18, which are provided on the concave or outer edges of the jaws 11 and 12 and are integral with the latter; the pressure of the ends of said spring 16 tends to turn said plates 17 and 18 and said jaws 11 and 12 on said pin 13 as a pivot in a direction to close the jaws 11 and 12.

To open the said jaws 11 and 12 the thumb-plates 17 and 18 are pressed towards each other

by the hand of the operator in opposition to the resistance or torsion of said spring 16.

The jaws 11 and 12 are provided with sets of teeth 19 and 20 respectively, which are positioned opposite each other adjacent to the concave edges of said jaws and are integral with the latter; the teeth 19 and 20 are of substantially the same length and may be formed by punching or striking from the metal of said jaws, leaving in the latter openings 19a and 20a respectively, 10 as shown.

The sets of teeth 19 and 20 are disposed to overlap each other at their outer ends and the overlapping positions of said ends are positioned midway between the jaws 11 and 12, as shown in 15 Fig. 2, thereby producing a bite which assists in gripping the layer or lock of hair and otherwise produces a more perfect action or operation of the hair waving device.

To limit the extent of the overlap of the teeth 20 19 and 20, which are preferably curved as shown, the closing motion or rotation of the jaws 11 and 12 towards each other is limited by means of one or more stops 21 which are shown as provided on the jaw 11 to abut against the jaw 12 in the closed 25 position of the device.

The stops 21 are shown as punched from the metal of the jaw 11 leaving therein openings 21a and located near the convex edge of the jaw 11.

In the modification of my hair waving device, 30 which is shown in Figs. 3 and 4, the sets of teeth on the jaws 31 and 32 have each thereon alternately long teeth 29 and short teeth 30; the teeth 29 on one set are positioned opposite the teeth 30 on the other set and vice versa. By this arrangement the teeth 29 and 30 act on more than one layer of hair at a time, thereby insuring a firmer grip on the hair.

The jaws 31 and 32 also have their opposite teeth disposed to overlap each other at their 40 outer ends; the ends of the teeth 30 in each set are shown as disposed to overlap the ends of the teeth 29 of the opposite set.

Stops 21 are shown as provided on the jaw 31 to abut against the jaw 32 when the jaws are 45 closed for limiting the rotation of the plates 31 and 32 on the pin 13 as a pivot under the influence of the spring 16, thereby also limiting the extent of the overlap of said teeth 29 and 30 at the outer ends thereof.

The teeth 29 and 30 are punched from the jaws 31 and 32 leaving in the latter the openings 29a and 30a, as shown in Fig. 4.

The stops 21 are also punched from the plate 31 leaving therein corresponding openings 21a. 55

Standard parts, such as thumb-plates 17 and 18, springs 16 and pivot pins 13 of hair waving devices are designated by the same numerals in the views of all the three modifications of my improved hair waving device.

The stops 21 and openings 21a which are hereinbefore described are also designated by the same numerals in the views of the three modifications of my hair waving device.

Variations are possible, and parts of my invention may be used without other parts.

I claim as my invention and desire to secure by Letters Patent:

1. In a hair waving device a pair of jaws pivotally connected to each other, teeth extending from each of said jaws towards the other jaw, said teeth to grip a layer of hair therebetween, a means for keeping said jaws in closed position and a means for opening said jaws, the teeth on the opposite jaws being positioned opposite each other and the corresponding opposite teeth of each pair of opposite teeth on said jaws being disposed to overlap each other at their outer ends in a plane positioned transversely to the pivot of said jaws, when the jaws are in a closed position, thereby producing a biting action by the opposite teeth of said jaws and insuring a firmer grip on the said hair.

2. The elements of claim 1, combined with

a means for limiting the rotation of said jaws on their pivot when the device is being closed and thereby limiting the overlapping of said ends to a desired extent.

3. The elements of claim 1, the teeth on each jaw being alternately longer and shorter, the longer teeth on each jaw being positioned opposite the shorter teeth on the other jaw, and vice versa said teeth thereby acting on more than one layer of hair at a time and thereby insuring a firmer grip on the hair.

4. In a hair waving device a pair of jaws, pivotally connected to each other, teeth extending from each of said jaws towards the other jaw, said teeth to a grip of layer of hair there between, a means for keeping said jaws in closed position and a means for opening said jaws, the teeth on the opposite jaws being disposed to overlap each other at their outer ends when the jaws are in closed position, thereby producing a biting action and insuring a firmer grip on the said hair, combined with one or more stops on one of said jaws to abut against the other jaw, whereby to limit the rotation of said jaws on their pivot, when the device is being closed and thereby limiting the overlapping of the said ends to a desired extent.

ARTHUR M. HERSCHENSOHN.
